(57) **CLAIM**

The ornamental design for a folding chair as shown and described.

DESCRIPTION

FIG. 1 is a perspective view from the top of a folding chair in an open configuration;

FIG. 2 is a front elevation view of the folding chair of FIG. 1 in the open configuration;
FIG. 3 is a rear elevation view of the folding chair of FIG. 1 in the open configuration;
FIG. 4 is a left side elevation view of the folding chair of FIG. 1 in the open configuration;
FIG. 5 is a right side elevation view of the folding chair of FIG. 1 in the open configuration;
FIG. 6 is a top plan view of the folding chair of FIG. 1 in the open configuration;
FIG. 7 is a bottom view of the folding chair of FIG. 1 in the open configuration;
FIG. 8 is a perspective view from the top of the folding chair of FIG. 1 in an elevated seat configuration;
FIG. 9 is a front elevation view of the folding chair of FIG. 1 in the elevated seat configuration;
FIG. 10 is a rear elevation view of the folding chair of FIG. 1 in the elevated seat configuration;
FIG. 11 is a left side elevation view of the folding chair of FIG. 1 in the elevated seat configuration;
FIG. 12 is a right side elevation view of the folding chair of FIG. 1 in the elevated seat configuration;
FIG. 13 is a top plan view of the folding chair of FIG. 1 in the elevated seat configuration;
FIG. 14 is a bottom view of the folding chair of FIG. 1 in the elevated seat configuration;
FIG. 15 is a perspective view from the top of the folding chair of FIG. 1 in a folded configuration;
FIG. 16 is a front elevation view of the folding chair of FIG. 1 in the folded configuration;
FIG. 17 is a rear elevation view of the folding chair of FIG. 1 in the folded configuration;
FIG. 18 is a left side elevation view of the folding chair of FIG. 1 in the folded configuration;
FIG. 19 is a right side elevation view of the folding chair of FIG. 1 in the folded configuration;
FIG. 20 is a top plan view of the folding chair of FIG. 1 in the folded configuration; and,
FIG. 21 is a bottom view of the folding chair of FIG. 1 in the folded configuration.
The dash-dash broken lines show portions of the folding chair that form no part of the claimed design. The dash-dot-dash broken lines show boundaries of the claimed design and form no part thereof.

1 Claim, 21 Drawing Sheets
